UNITED STATES PATENT OFFICE
2,607,290

DUPLICATOR DEVICE
Carl B. Runge, Chicago, Ill.
Application April 11, 1949, Serial No. 86,839
1 Claim. (Cl. 101—126)

1 My invention relates to improvement means in duplicators, and bears particular relationship to small, post-card size, hand-operated duplicators used in connection with stencils.

A prime object of my invention is to provide improvements in the operation of post-card size duplicators to prevent the card stock being printed from slipping and getting out of register during the printing operation.

A further important object of my invention is to provide duplicator improvement means for accurately locating the rocker assembly on the printing bed at the beginning of the printing or inking operation.

A further object of my invention is to provide adjustable resilient stop card means for use in connection with card stock of different sizes.

A still further object of my invention is to provide an improvement in the tightening and locking means for the stencil which is used in connection with this type of duplicator.

A further important object of my invention is to provide a printing bed wherein the body, leg portions and lateral guide rails are stamped from a single sheet of metal, simplifying the production thereof.

Other objects and advantages embraced in my invention will be disclosed in the following description and the accompanying illustrations, wherein like parts are referred to by like numerals and in which:

Fig. 1 is a perspective view of a stencil-type duplicator of post-card size showing my improvements in connection therewith, and showing card stock in printing position on the printing bed assembly with the rocker assembly in position ready for printing.

Fig. 2 is a perspective view of my invention showing the rocker assembly resting upon the printing bed midway of the printing cycle.

Fig. 3 is a perspective view showing the bottom of the perforated arcuate rocker assembly and showing the capillary ink pad in a swept-back position, and the stencil paper in exploded position in relation thereto.

Fig. 4 is an enlarged, cross-sectional view of my invention taken substantially on line 4—4 on Fig. 2 and showing details of the attaching of the capillary ink pad and stencil to the rocker assembly.

Fig. 5 is an enlarged, fragmentary, cross-sectional view taken substantially on line 5—5 on Fig. 4 and showing the vented filler cap means of my invention.

Fig. 6 is an enlarged, fragmentary, perspective view showing the rocker locating means in

connection with the printing bed assembly of my invention.

Fig. 7 is a side view showing the printing bed assembly of my invention and showing in phantom lines three consecutive positions of the rocker assembly during the printing operation.

Referring to the illustrations, my invention is generally designated 8 and consists of a printing bed assembly 9, and a rocker assembly 10. The printing bed assembly consists of a printing bed portion 11, side portions 47 and 48, lateral rocker guide portions 13, and end supports 12. The end supports 12 are formed into leg portions 50. Adjustable resilient stop means 14 are attached to side portion 47, one at either end thereof, and held in place by washer and screw means 15 through the eye portions 16. The said stop means 14, being resilient, do not interfere with the rocker assembly during printing. The rocker guide portions 13 are reduced to form cradled portions 17 adjacent side 48. Slotted initial gauge portions 18 are formed in printing bed 11 adjacent the recessed cradled portions 17.

The rocker assembly 10 consists of the rocker body 21, having an arcuate rocker surface 22, with ink feeding perforations 23 formed over its entire surface. Ink, designated 46, is contained in ink compartment 24. Rocker locating ears 25 extend past arcuate rocker surface 22 and engage slotted initial gauge portions 18 at the start of the inking operation, as shown in Figs. 1 and 7. A capillary ink pad 26, which may be preferably of fabric or cloth, has rod retaining pockets 27 and 28 formed on its two opposite edges, which, in association with ink pad retaining rod 29 and ink pad securing rod 30 maintain the said capillary ink pad 26 stretched tautly over arcuate rocker surface 22. The said filter retaining rod 29 is secured in aligned holes 29' in ears 25. The filter securing rod 30 is maintained in snapping engagement by rod holding notches 31 in ears 32, which project past arcuate rocker surface 22 opposite from rocker locating ears 25.

A stencil 33 is provided with attaching slots 34 to engage stencil attaching lugs 35 spaced in alignment between ears 32 on rocker body 31. In position, the stencil 33 is taughtly stretched over capillary ink pad 26 and its free edge 36 is tightened and locked by stencil tightening and locking rod 37 in snapping engagement between ink pad retaining rod 29 and stepped rod seating fingers 38, on rocker body 21. The said stepped rod seating fingers 38 are sufficiently long to permit the finger tip designated 49 shown in phantom lines in Fig. 4 to be inserted between stencil tight-

ening and locking rod 37 and rocker body 21 for ejecting the said stencil tightening and locking rod preparatory to releasing stencil 33.

A roller manipulating knob 39 is centrally located on the top of rocker assembly 10, held by screw 40 together with threaded flange bushing 41, which is fixed in the top of rocker body 21. A vented filler cap 42 is mounted over threaded bushing 43 on the top of rocker body 21 and sealed thereagainst by gasket 45. Air vent tube 44 connects the top of filler cap 42 with the interior of ink compartment 24.

The filter retaining rod 29 has trunnion like extensions 51, to engage the cradle portions 17 at the start of the inking procedure, and functions to position the rocker assembly 10 in relation to printing bed 11 and the card stock 19 or 20 as shown in Fig. 1. The said card stock 19 or 20 may be of any size up to the width of the printing bed 11 and is held in place by the adjustable resilient stop means 14. The said printing card stock is further held in secure registry at the start of the printing operation by the edge of the arcuate rocker surface 22. This is best illustrated in Figs. 1 and 7. Fig. 7 further illustrates the various positions of rocker assembly 10 during the card printing procedure.

To prepare the rocker assembly for printing, the capillary ink pad 26 is stretched between filter retaining rod 29 and filter securing rod 30 over arcuate rocker surface 22. The prepared stencil 33 is stretched over ink pad 26 and locked by stencil tightening and locking rod 37. After filling ink compartment 24 with ink 46 through filler cap 42, the rocker assembly 10 is positioned upon printing bed assembly 9, as shown in Fig. 1, with rocker locating ears 25 within slotted initial gauge portions 18 and trunnion like extensions 51 resting against cradled portions 17. Adjustable resilient stop means 14 are adjusted to fit the card stock either of the size 19 or 20, as shown in Fig. 1.

The rocker assembly 10 is rocked over the printing bed 9, as illustrated by various positions in phantom lines in Fig. 7, in which it will be observed that the edge of arcuate rocker surface 22 engages card stock 19 or 20, preventing the slipping thereof which would cause the card to print out of register. It will be observed that the said arcuate rocker surface 22 is in contact with printing bed 9 through-out printing operation, and is laterally guided by lateral rocker guide portions 13.

The cradled portions 17 and slotted initial gauge portions 18, together with ears 25 and trunnion like extensions 51, provide a foolproof means of locating rocker assembly 10 in the initial stage of the printing operation. The card stock designated 19 or 20 may be of post-card size or may be as small as a calling card or business card.

Important advantages in connection with my invention reside in the ease with which the stencil is secured, tightened and locked over the arcuate printing surface 22, by means of the stepped rod seating fingers 38 in connection with the stencil tightening and locking rod 37.

A prime advantage in connection with my invention is the hereinabove described rocker assembly locating and positioning means which also

holds the card stock securely in place at the beginning and throughout the printing operation to insure that the card will be printed in true registry.

5 A still further advantage in connection with my invention is the simple, one-piece structure of the printing bed assembly and the adjustable resilient stop means attached to the edge thereof.

10 It is to be understood that changes may be made in the construction and in the combination and arrangement of the several parts, provided that such changes fall within the scope of the appended claim.

15 Although I have herein described rather succinctly the nature and use of my invention so that persons skilled in the art will have no difficulty apprising themselves of the teachings thereof and, inasmuch as the disclosure is susceptible of various alterations, modifications, and improvements, I hereby reserve the right to all modifications, alterations, and improvements falling within the scope and spirit of my invention, as well as any modifications that are embraced suggestively in the accompanying drawings, and any that may come within the purview of the foregoing description; my invention to be limited only by the appended claim.

20 Having thus disclosed and revealed my invention, what I claim as new and desire to secure by Letters Patent is:

25 Improved duplicator means comprising, printing bed assembly means provided with a centrally disposed and depressed printing bed portion defining lateral rocker guide means, rocker assembly means of a magnitude commensurate with the distance between the said lateral rocker guide means, the said rocker assembly means being provided with rocker locating ears on one end thereof, slotted initial gauge means provided on the said lateral rocker guide means adapted to locate initially and guide the said rocker locating ears, undercut cradle portions on the said lateral rocker guide means, and trunnion-like means on the said rocker assembly means operating on the said undercut cradle portions, the said trunnion-like means in concert with the said undercut cradle portions forming auxiliary locating means to maintain longitudinal location of the said rocker assembly during the rocking period when the said rocker locating ears emerge from the said slotted initial gauge means thus augmenting the locating function of the said rocker locating ears and the said slotted initial gauge means.

30 C. B. RUNGE.
